UNITED STATES PATENT OFFICE.

WILLIAM L. WILSON, OF GREENVILLE, SOUTH CAROLINA, AND EARL E. LOVERN, OF NEWNAN, GEORGIA.

WAREHOUSE CAR.

Application filed June 12, 1922. Serial No. 567,632.

To all whom it may concern:

Be it known that we, WILLIAM L. WILSON and EARL E. LOVERN, citizens of the United States, residing at Greenville and Newnan, respectively, in the counties of Greenville and Coweta and States of South Carolina and Georgia, have invented certain new and useful Improvements in Warehouse Cars, of which the following is a specification.

Our invention relates to a warehouse car or roving box and particularly to this type of vehicle adapted for use in textile mills or factories for transporting yarns, bobbins, spools, quills, etc.

In textile mills or factories it is customary to employ a wheeled vehicle and to load the same with various types of material such as yarn, either on spools, bobbins, quills, or in hanks; so that the same may be conveniently transported from one section of the mill to another.

Heretofore the body portion of these containers comprised a box having a solid bottom which presented the possibility of dirt, trash, or other foreign matter accumulating therein, which, when coming into contact with the yarn or other material, soiled the same and reduced its value so that it was necessary to sell this soiled yarn as a "seconds."

It is the object, therefore, of this invention to provide a warehouse car with a bottom which will prevent the accumulation of dirt or other foreign matter, it being so constructed as to permit such foreign material to escape.

The construction is such that the box will be self-cleaning owing to the fact that dirt settling into bottom of the box is directed toward an open section thereof. Therefore a warehouse car constructed in accordance with this invention has the advantages that the material conveyed therein will not become soiled, and the concurrent loss in sales value of the material is therefore eliminated.

The invention furthermore consists in the novel construction and arrangement of parts hereinafter more fully described and illustrated in the accompanying specification and drawings.

In the drawings;

Figure 1 is a perspective view of a warehouse car constructed in accordance with our present invention;

Fig. 2 is a top plan view of the same;

Fig. 3 is a fragmentary transverse section; and,

Fig. 4 is a fragmentary detail perspective view of the bottom.

Referring now more particularly to the drawings wherein like reference characters indicate like parts, it will be seen that there is illustrated a box 10 which may be of any preferred design and construction and be made of any suitable material. This box may be made of vulcanized sheet fiber reinforced by wooden bands or of vulcanized sheet fiber with thin sheets of steel riveted thereon and reinforced by wooden bands secured with metal guards at the corners, or it may be made of steel sheets alone. In this present instance the box is shown as provided with sides 11 and ends 12 reinforced by wooden bands 13 and secured at the corners by metal shields 14. While a particular construction of box is shown by way of illustration it should be understood that any desired type of box may be employed.

The bottom of the receptacle or car body is composed of two-ply material, comprising a top section 15 and a bottom section 16. The top section 15 is bevelled or inclined from its outer edge inwardly and downwardly, as clearly illustrated in Figs. 3 and 4. The bottom section of the two-ply bottom is preferably of equal thickness throughout. The two sections of the bottom are secured together at suitable intervals by bolts, screws, rivets, or the like 13.

The bottom is cut away centrally thereof as indicated at 18 and for the purpose of providing a support, a plurality of bars or rods 19 are arranged in spaced relation across the opening 18. These bars or rods may be made of solid fiber, hollow fiber rods, or hollow fiber rods reinforced with metal rods. These spaced rods provide a grating which extends over a portion of the bottom thereby providing an exit for dirt or other foreign material in the car body. These rods 19 are preferably held in place by registering semi-circular recesses formed in

the opposed faces of the sections 15 and 16, thereby providing pockets 20, into which the ends of the rods 19 extend.

For enabling the receptacle to be conveniently moved from place to place there is provided preferably four wheels 21, supported in suitable frames 22 which are secured to the bottom section 16 of the two-ply bottom. It will be immediately obvious, however, that the number and position of these wheels may be varied to suit the necessities of each particular condition.

Obviously, therefore, the material to be conveyed, such for instance as yarn on spools, bobbins, quills, or in hanks, may be placed in the receptacle in the usual manner. However, any foreign material which may happen to be in the receptacle will be directed to the opening 18 by the inclination 20 of the top section 15 of the two-ply bottom.

The vibration of the receptacle in transit will assist materially in dislodging any dirt which may have a propensity for remaining in the receptacle. Thus the contents of the receptacle may be transported without danger of the same becoming soiled and consequently unfit for use as first-class material.

The construction described herein is capable of being manufactured cheaply without sacrificing in any degree its durability and at the same time provides a structure wherein the results sought to be accomplished are efficiently achieved.

While the details of construction herein described and illustrated have been found by us to be efficient in every respect, it is

not our intention that the invention be unnecessarily limited but reservation is made to make such changes and modifications as may come within the purview of the accompanying claims. 40

Having thus described our invention, what is claimed is:

1. In a warehouse car of the class described a bottom therefor formed of two sections of material secured together, said bottom being formed with a centrally disposed opening, the upper section of said bottom being inclined from the edge thereof downwardly toward said opening, the opposed faces of said sections being formed with recesses and a plurality of bars extending across said opening with their ends secured in the pockets formed by said recesses. 50 55

2. A bottom for a warehouse car formed of two sections of material, means for securing said sections together, said bottom being formed with a centrally disposed opening, the top section of said bottom being inclined from the edge thereof downwardly toward said opening, the lower section of the bottom being of equal thickness forming a flat lower face, the opposed faces of said sections being formed with semi-circular recesses, a plurality of bars extending across said openings with their ends resting in the pockets formed by said recesses and a plurality of wheels secured to the flat lower face outer surface of said lower section. 60 65 70

In testimony whereof we affix our signatures.

WILLIAM L. WILSON.
EARL E. LOVERN.
